UNITED STATES PATENT OFFICE

FRANK J. WINDER, OF BRACKENRIDGE, PENNSYLVANIA, ASSIGNOR TO ALLEGHENY STEEL COMPANY, A CORPORATION OF PENNSYLVANIA

CONTINUOUS-HEAT ANNEALING FURNACE

Application filed March 30, 1928. Serial No. 265,924.

This invention relates to the annealing of steel, iron, or alloy metal.

In the manufacture of all types of sheets, it is advisable, as far as possible, to secure flatness and it is therefore advisable to have the sheets flat during annealing thereof. It is also advisable to prevent scratching or otherwise marring the sheets during annealing.

10 In the manufacture of certain types of sheets, such as full finished sheets, it is advisable to carry on the annealing in a non-oxidizing or in a reducing atmosphere, while with other types of sheets, such as silicon steel sheets, it is advisable to carry on the annealing in such a manner that the gases given off from the material during annealing are carried away in order to prevent re-absorption thereof.

20 With sheets such as full finished sheets, it is advisable to hold the same in the non-oxidizing or reducing atmosphere until they are cooled to a point below that at which rapid oxidization or free scaling occurs and 25 it is advisable from many angles with all types of sheets to carry on the annealing as a continuous process.

An object of this invention is to provide a method of and apparatus for carrying on 30 the continuous annealing of steel, iron or alloy sheets in suspended and flat or substantially flat condition and out of contact with any supporting means except along the upper edge thereof.

35 Another object is to provide a method of and apparatus for carrying on the continuous annealing of sheets in such a manner or by such a means that the sheets are suspended and depend from a support capable of continuously moving the sheets during the annealing operation and until the same have cooled to the desired temperature.

Another object is to provide a method of and apparatus for carrying out the continuous annealing of sheets, wherein the apparatus is provided with an improved means for supporting the sheets during the annealing operation, such means being capable of supporting two rows of sheets and continuously moving the sheets during the anneal-

ing operation and thereby increasing the production of such sheets and rendering this production less expensive.

A still further object is to produce an annealing furnace which, by but slight changes, is adapted for carrying on the annealing of sheets in either a reducing or non-oxidizing atmosphere or in such a manner that free circulation is provided, whereby gas given off from the sheets during annealing may be rapidly carried away in order to prevent re-absorption thereof.

In a general way, the method consists in suspending the sheets along one edge thereof to a support adapted to carry them edgewise and in succession through a relatively long annealing chamber. In the case of full finished sheets, the chamber is more or less tightly sealed against the ingress of air and is preferably heated in such a manner that either a non-oxidizing or reducing atmosphere is obtained within the chamber. In the case of other types of sheets in which it is not necessary to maintain any particular kind of atmosphere, the ends of the annealing chamber are left open in order to provide more or less circulation through the same.

These as well as other objects which will be apparent to those skilled in this particular art are attained by means of the method and apparatus described in the accompanying specification and the more or less diagrammatic illustration in the drawings accompanying and forming a part of this application.

In the drawings, Fig. 1 is a broken top plan view partly in horizontal section of a furnace embodying the invention and Fig. 2 is an end elevation partly broken away looking towards the discharge end at the left of Fig. 1.

The annealing furnace is preferably of such length and is so heated that a relatively cool zone is provided through which the sheets to be annealed must pass before being subjected to the annealing temperature and in which the sheets are preliminarily heated before being subjected to the final annealing temperature. As desired, the furnace may

- be provided with a non-oxidizing or reducing atmosphere and the furnace is preferably of such a length sufficient to allow the sheets passing therethrough to be pre-heated therein, then raised to the annealing temperature, maintained at that temperature the required length of time and then cooled within the furnace and adjacent the discharge end thereof to a temperature at which no rapid oxidation or free scaling occurs.
- 5 The furnace is formed from suitable refractory material with a floor 11, side walls 12 and 13 and roof 14. The furnace is supported on a concrete base 15. Burner openings 16 are provided at suitable intervals throughout its length for accommodating the burners employed for heating the interior of the furnace chamber and these burners are preferably of the type known as "surface combustion". Obviously the furnace may also be designed for employing other kinds of fuel such as coal, coke and the like. The furnace is also provided with a grate 17 for the well known purpose.
- 10 The inner surfaces of the walls 12 and 13 and roof 14 are provided with a lining 18 composed of a refractory metal such as an alloy having a high chromium content and capable of withstanding the heat of the furnace. The walls and roofs of the furnace may be constructed so as to form a substantially closed chamber and may be provided with relatively narrow slits or openings 19 in each end for the entrance of sheets thereto and discharge of sheets from the furnace chamber.
- 15 These openings may be of such small areas as to prevent ingress of air to the furnace against the furnace pressure. Each opening or passage 19 may, if desired, be normally closed by yieldingly mounted doors 21, which may be yieldingly pressed into closed position by any suitable mechanism, not shown.
- 20 Provision is made for passing separate rows of sheets continuously through the furnace. These sheets may be of the same or different gauge and the drawings illustrate the furnace as equipped for two such rows, each row comprising two rows of sheets and the sheets of one row may be conveyed through the furnace at any predetermined speed independent of the sheets of the other row.
- 25 The sheets are continuously moved edge-wise through the furnace by the conveying mechanism provided. In the particular form of conveyor illustrated in the drawing, endless roller chains 22 formed of suitable metal links 23 are provided, the links 23 being connected together by shafts provided with rollers 25 on each of their ends, which are so mounted in the side walls of the furnace, that one run of each chain extends through the furnace chamber, entering the chamber
- 30 through one of the openings 26 at one end

and emerging from the chamber through an aligned opening 26 at the opposite end. The chains pass around associated sprocket wheels 27 mounted on supporting shafts 28 adapted to be rotated from any suitable source of power 29 through any desired reduction gear 31. At the other end of the furnace, each chain is mounted upon an associated idler sprocket wheel 32 and adapted to pass around the associated sprocket wheels in a continuous manner.

35 The roller chains 22 are supported and kept in position throughout the entire length of the furnace by bearing castings 33, 34 and 35. The bearing castings 33, 34 and 35 are positioned in the respective side walls and held in position with one another by any suitable means, such as shown at 36. The side walls 12 and 13 are supported by suitable buck-stays 40 embedded in the concrete base 15 and extended upwardly the entire height of the furnace and the bearing casting 34 is further re-enforced by suitable metal supports 37 riveted or otherwise fixed to the buck-stays 40 and extending inwardly and engaging the top of the bearing casting 34 to prevent any upward movement of this casting.

40 The chains 22 are provided with spaced arms 38 extending outwardly into the furnace chamber. These arms terminate in a downwardly extending arrow shaped end 39 and thereby provide projections 41 and 42 for engaging the bent edges of the sheets. The arms 38 may be integral with the links 23 or riveted, bolted, or otherwise firmly secured thereto.

45 It can be seen from the above that the roller chain is supported throughout the length of the furnace and is held in position by the bearing castings 33, 34 and 35. The present roller chain, which is supported and maintained in position throughout the length of the furnace, provides a sheet supporting means capable of supporting two rows of sheets and will not sag due to the weight of the sheets during their passage through the furnace.

50 In practicing the invention, the sheets are positioned on the arrow head 39 of the arms 38 at the entrance to the furnace, the sheets are then passed through the furnace at such speed as may be desired and the annealed sheets are readily removed from the conveyor as it emerges from the furnace.

55 An important advantage of the present structure is the positioning of the conveyors so as to be supported by the side walls and the particular construction of the conveyor which renders it capable of carrying through the furnace, a greater number of sheets, to be annealed and thereby reduces the cost of such sheets.

60 Another important advantage of the present construction is the lining of the inner surface of the furnace with a refractory metal

having sufficient characteristics to withstand the heat of the furnace and thereby prevent the cracking and falling off of the material from which the side walls are constructed. 5 This does not only prevent undesirable particles from coming in contact with the sheets being treated, but maintains the furnace pressure and increases the life of the furnace indefinitely.

10 Sheets of different gauges may be simultaneously annealed by suspending those of one gauge from one conveyor and those of another gauge from the other conveyor. The speed of the conveyors will then be regulated so as to cause the sheets to be subjected to the temperature for periods proportional to the gauge thereof.

What I claim as new and desire to secure by Letters Patent is:—

20 1. The combination in a continuous furnace, of a heating chamber, a conveyor chamber located on top of one side wall of the heating chamber and below the roof thereof, a conveyor having one run thereof movable through said conveyor chamber and sheet supporting members carried by said conveyor and extending from said conveyor chamber into the heating chamber.

25 2. The combination in a continuous furnace, of a heating chamber having a closed top, conveyor chambers located below the heating chamber top and above the side walls of said chamber, endless conveyors each having one run thereof located in one of said conveyor chambers and sheet supports extending from the conveyor runs within said conveyor chambers into said heating chamber.

In testimony whereof, I have hereunto subscribed my name this 17th day of March, 1928.

FRANK J. WINDER.
